F. W. SEVERIN

INTERNAL COMBUSTION ENGINE

Filed April 14, 1924

Inventor
Frank W. Severin
By Fred Gerlach
Atty.

UNITED STATES PATENT OFFICE.

FRANK W. SEVERIN, OF WILMETTE, ILLINOIS, ASSIGNOR TO VENN-SEVERIN MACHINE CO., OF CHICAGO, ILLINOIS, A CORPORATION OF ILLINOIS.

INTERNAL-COMBUSTION ENGINE.

Application filed April 14, 1924. Serial No. 706,293.

To all whom it may concern:

Be it known that I, FRANK W. SEVERIN, a citizen of the United States, and a resident of Wilmette, in the county of Cook and State of Illinois, have invented certain new and useful Improvements in Internal-Combustion Engines, of which the following is a full, clear, and exact description.

The invention relates to internal combustion engines of that type in which the working fluid is injected directly into the combustion-chamber, and its primary object is to provide an improved construction which will produce thorough and even intermingling in said chamber of the fuel and air compressed by the piston in the working-cylinder, delivering the compressed air into the chamber so that it will not be baffled against and condense the injected oil, and will be dispersed to avoid currents which will tend to localize the oil or interfere with effective intermingling of air and oil necessary for efficient combustion.

The invention consists in the several novel features hereinafter set forth and more particularly defined by claims at the conclusion hereof.

In the drawings: Fig. 1 is a longitudinal section of an oil engine embodying the invention. Fig. 2 is a section taken on line 2-2 of Fig. 1.

The invention is exemplified in an engine of the two-cycle type which comprises a water-jacketed working-cylinder 3, in which is slidably mounted the working-piston 4 which is connected by a pitman 5 to a crank-shaft, as well understood in the art; a water-jacketed head 6 for said cylinder and which is secured thereto by bolts 7; a cylinder 8, in which the body or central portion of the combustion-chamber 8^a is formed; a water-jacketed head 9; and bolts 10 which extend through the head 9 and into the head 6 and clamp the cylinder 8 between said heads. An injector 11 of any suitable construction, is secured centrally in the head 9 and is of the type which is adapted to discharge a spray of oil in variation formation or direction and downwardly and angularly to spread it more or less and proportionately to the load. An electric firing-plug 12 extends through the cylinder 8 to ignite the combustible mixture

in the chamber 8^a. The body of the combustion or firing chamber 8^a is formed in cylinder 8, and at one of its ends it has a curved or concave portion 8^b formed in head 9, through which the oil is injected, and a spherically concave portion 8^c in the cylinder-head 6. The latter is provided with a central opening 15 which provides a communication between the working-cylinder and the combustion-chamber. The outer margin of the upper end of the piston is tapered and has two relatively angled conoidal portions, as at 16, 16^a, conformably to the correspondingly tapered portions 17, 17^a in the head 6. A recess 18, having a curved wall 18^a, is formed in the lower end of cylinder-head 6 between conoidal portion 17^a and opening 15, for the passage of the compressed air from the space between the conoidal surfaces of the piston and cylinder-head 6. The central portion of the piston-end is adapted to move into position to partially fill recess 18 when the piston is at the outer end of its stroke. The opening 15 between the combustion chamber and the space in the lower end of head 6 forms a constriction between recess 18 and chamber-end 8^b, but is of sufficient area to prevent jetting of, or giving fixed direction flow to, the air passing from the working cylinder into the lower end of the combustion-chamber. The edge of opening 15 between recess 18 and the lower concave end 8^b of the combustion-chamber approximates a knife-edge to avoid giving definite upward or longitudinal direction to the compressed air passing into the combustion-chamber so the air will flow upwardly and spread throughout substantially the entire area of chamber 8^a. The combustion-chamber above constriction-opening 15 has sufficient cubic area to permit the compressed air to pass outwardly and upwardly in the lower concave end of said chamber following the concavity of said end as generally indicated by arrows in Fig. 1, and to get behind or around the charge of vapor forced into the chamber 8^a, and also to provide for sufficient expansion to liberate the heat from combustion. The recess 18 is small relatively to the chamber 8^a and the arc of wall 18^a is such as to cause the fuel in the combustion chamber to be reversed in flow after impacting against the piston and

deflect the air in turbulence in the combustion-chamber 8^a to completely decompose the fuel into carbon-dioxide and ash.

In practice, it has been found that in the 5 operation of oil engines, a desideratum is to avoid giving a definite direction or nozzle effect to the air, because when this occurs, the oil and air are impacted against each other, and this tends to condense the oil before combustion.

In operation, the piston 4, during its up-stroke and after the products of combustion from the previous power-stroke have been discharged, will compress air in the upper 10 end of the working cylinder and force it from the cylinder around the constriction-opening 15. The air will not be jetted through said opening and pass with directional force into and through the combustion-chamber, but will pass outwardly and 15 upwardly and be dispersed somewhat uniformly and without definite direction throughout the entire width of the combustion chamber. Consequently, each charge of 20 oil injected and sprayed into the combustion-chamber through injector 11 will not be baffled and condensed by the air, but will set up a disturbance to effect a substantially uniformly combustible mixture which, 25 when it reaches its maximum compression in the combustion chamber, will be ignited by the plug 12 to impart a power-stroke to the piston. The recess 18, being formed to permit reversal of the products impacted 30 against the piston, will cause any unconsumed fuel to pass back into chamber 8^a where it will commingle with the products to result in complete combustion.

In these engines, the oil is injected, while 35 the crank-shaft is travelling, from 30° to 10° of its upper dead-center and momentarily. A desideratum is to inject the oil at substantially the point of greatest activity of the air and to spray the oil in different directions or with more or less spread 40 to produce the diffusion necessary for efficient combustion and according to the variation in the volume of the oil injected. The invention exemplifies a construction in 45 which this desired result is attained, because it provides for thoroughly mixing the oil and air without jetting or directional flow of the air which tends to condense the oil and for mixing with air in substantially 50 uniform state of activity across the entire combustion-chamber.

The invention is not to be understood as 55 restricted to the details set forth, since these may be modified within the scope of the appended claims, without departing from the spirit and scope of the invention.

Having thus described the invention, what 60 I claim as new and desire to secure by Letters Patent, is:

1. In an oil engine, the combination of a

working cylinder, a piston slidable therein, a combustion-chamber connected to the outer end of and coaxial with the cylinder, an injector connected to spray oil into the combustion chamber, an annular substantially 70 knife-edge constriction with a central opening between the cylinder and the chamber, and an annular recess in the cylinder contiguous to said edge, said recess being disposed between the area traversed by the piston and the constriction, said recess and constriction being adapted to form a direction-destroying passage for the compressed fluid from the cylinder to the combustion chamber to prevent jetting or definite directional 80 flow of the fluid from the cylinder, the combustion chamber having sufficient cubic area to permit the fluid from the cylinder to disperse uniformly throughout the width of the combustion chamber and 85 to prevent baffling which will condense the oil.

2. In an oil engine, the combination of a working cylinder, a piston slidable therein, a combustion chamber connected to the 90 outer end of and coaxial with the cylinder, an injector connected to spray oil into the combustion-chamber, an annular substantially knife-edge constriction with a central opening between the cylinder and the chamber, and a wall-portion sharply and outwardly curved from said edge to the cylinder forming an annular recess in the cylinder between the area traversed by the piston and said edge, said recess and constriction being shaped to form a direction-destroying passage for the compressed fluid from the cylinder to the combustion chamber to prevent jetting or definite directional 95 flow of the fluid from the cylinder, the combustion chamber having sufficient cubic area to permit the fluid from the cylinder to disperse uniformly throughout the width of the combustion chamber and to prevent 100 baffling which will condense the oil.

3. In an oil engine, the combination of a working cylinder having a tapered portion at the outer end of the cylinder, a piston slidable in the cylinder and provided with a correspondingly tapered portion to enter 115 the tapered portion of the cylinder, a combustion-chamber connected to the outer end of and coaxial with the cylinder, an injector connected to spray oil into the combustion chamber, an annular substantially 120 knife-edge constriction with a central opening between the cylinder and the chamber, and an annular recess in the cylinder contiguous to said edge, said recess being disposed between the area traversed by the piston and the constriction, said recess and constriction being shaped to form a direction-destroying passage for the compressed fluid from the cylinder to the combustion chamber 125 to prevent jetting or definite directional 130 flow of the fluid from the cylinder, the combustion chamber having sufficient cubic area to permit the fluid from the cylinder to disperse uniformly throughout the width of the combustion chamber and to prevent baffling which will condense the oil.

- flow of the fluid from the cylinder, the combustion chamber having sufficient cubic area to permit the fluid from the cylinder to disperse uniformly throughout the width of the combustion chamber and to prevent baffling which will condense the oil, the tapered portions of the cylinder and piston being formed to deflect the fluid in the recess.
4. In an oil engine, the combination of a casing provided with a working cylinder, a head secured to the outer end of the casing, a piston slideable in the casing, a cylinder separate from and adjacent the outer end of said head and forming the body of a combustion-chamber, a separate head at the outer end of the latter cylinder, means for securing said heads together with the combustion-chamber cylinder therebetween, an injector in the outer end of the combustion-chamber head to spray oil into the outer end of the combustion chamber, the head between said cylinders being formed with an annular constriction which is of sufficient area and so short as to avoid jetting or giving definite direction to the compressed air from the cylinder, and having a concave portion between said constriction and the end of the cylinder forming the body of the combustion chamber, and having a recess between the constriction and the outer end of the working cylinder, the combustion-chamber having sufficient cubic area to permit the compressed air from the cylinder to spread uniformly throughout the width of the combustion-chamber and to avoid baffling which will condense the oil, and ignition means for the mixture in the chamber.
5. In an oil engine, the combination of a casing provided with a working cylinder, a head secured to the outer end of the casing and having a tapered portion contiguous to the outer end of the cylinder, a piston slideable in the casing and provided with a tapered portion fitting substantially in the tapered portion in said head, a cylinder separate from and adjacent the outer end of said head and forming the body of a combustion-chamber, a separate head at the outer end of the latter cylinder, means for securing said heads together with the combustion-chamber cylinder therebetween, an injector in the combustion-chamber head to spray oil into the outer end of the combustion chamber, the head between said cylinders being formed with an annular constriction which is of sufficient area and so short as to avoid jetting or giving definite direction to the compressed air from the cylinder, and having a concave portion between said constriction and the end of the cylinder forming the body of the combustion-chamber, and having a recess between the constriction and the tapered portion at the outer end of the working cylinder, the combustion-chamber having sufficient cubic area to permit the compressed air from the cylinder to spread uniformly throughout the width of the combustion-chamber and to avoid baffling which will condense the oil, and ignition means for the mixture in the chamber.

Signed at Chicago, Illinois, this 18th day of February, 1924.

FRANK W. SEVERIN.
